UNITED STATES PATENT OFFICE.

WARREN R. VALENTINE, OF FORD CITY, PENNSYLVANIA.

RUNNER FOR GRINDING PLATE-GLASS.

1,101,046.

Specification of Letters Patent. Patented June 23, 1914.

Application filed January 6, 1911. Serial No. 601,148.

To all whom it may concern:

Be it known that I, WARREN R. VALENTINE, residing at Ford City, in the county of Armstrong and State of Pennsylvania, a citizen of the United States, have invented or discovered certain new and useful Improvements in Runners for Grinding Plate-Glass, of which improvements the following is a specification.

10 In the operation of grinding plate glass, the unground plates are laid edge to edge upon a horizontal rotatable table, and are cemented or otherwise secured thereon. Rotatably suspended above the table are one or 15 more "runners," usually of circular form, having a grinding surface made up of iron blocks which bear upon the surface of the glass. The table is rotated by suitable means, and the runners are usually frictionally rotated, the grinding being accomplished by a suitable grit, (usually sand or emery), mixed with water, which is fed upon the surface of the glass, and becomes interposed between the glass and the runner- 20 blocks. In order to in a measure cushion the runner-blocks they have usually been secured to a wooden deck, the upper face of which has either been more or less open, and thus exposed to the water and grit used in 25 grinding, or if protected from such ingress of water and grit, the protection has been of such a character as to permit localized lodgment of grit thereon. The weight of such lodged grit frequently causes the deck 30 to bear unevenly upon the glass. This causes not only uneven grinding, but uneven wearing of the runner-blocks, so that the latter must be frequently renewed. Also, it being necessary to use different grades of grit in 35 successive steps of grinding a plate, it has been difficult to thoroughly cleanse the runner between steps; the result often being that coarse grains of grit become mingled with the finer grains intended to be used, thereby scratching or otherwise marring the 40 glass.

It is the object of the invention to overcome these difficulties, by providing a grinding-runner in which not only the deck is 45 practically closed against the intrusion of water and grit, and the upper surface of the closure is so formed as not to permit lodgment of grit thereon, but the frame of the runner is practically rigid, so that there will be little or no warping, sagging or co. forming to the uneven thickness of the glass, and

the runner-blocks will bear uniformly upon the glass so as to first grind away the thicker portions or excrescences and reduce the glass to uniform thickness and then grind evenly 60 over the entire surface. Thus the grinding will be uniform, and the runner-blocks being worn down uniformly, will have a much longer life. Also by providing a new shape of runner-block a more even distribution of 65 the grit is accomplished, and the grit is in great measure prevented from flying out from under the runner.

In the accompanying drawings forming a part of this specification, Figure 1 is a plan view of a grinding-runner embodying the invention, with the central cap removed. Fig. 2 is a sectional view on the line II—II of Fig. 1, showing the cap in place. Figs. 3 and 4 are views, in elevation and inverted 75 plan respectively, of a portion of a runner-bar, showing the improved shape of runner-bar. Fig. 5 is an inverted plan view showing a portion of the grinding-face of the runner.

The runner is provided with a frame 1, which may be of any suitable form, of substantial rigidity, and is herein shown as a single iron casting of the form of a circular inverted box, open at the center, so as to 80 have an annular web 2, and the arms 3 branching from the central boss 4, with supplemental arms or ribs 5 depending from the web 2 as desired. The arms and ribs 3 and 5 have flanges 6 at their lower edges, 85 and a second boss 7 at the inner edge of the web 2 is flanged in like manner, as well as the exterior wall 8 of the casting.

The lower faces of the flanges are accurately finished to provide an even bearing 90 surface for the planks which make up the wooden deck 9, and which are secured beneath the flanges in any suitable way, as by means of bolts 10, the lower heads of which, (not shown), should be countersunk in the 95 planks. The runner-blocks 11, which are preferably of a slightly tapering hexagonal form, are formed on the cast iron runner-bars 12. These bars may be fastened to the lower face of the deck 9 by any suitable 100 means, as by screws 13 passing through holes 14 in the bars, thus forming collectively a metallic grinding-shoe.

The cap 15 may be of any suitable form to close the opening in the top of the runner, and to permit of its rotatable suspension. It is herein shown as an iron casting 110

having a central shaft 16 and an outwardly flaring skirt 17. The edge of the skirt is bolted to the boss 7, as shown, so that the annular web 2 and the cap 15 together form 5 a closed impermeable roof for the runner, preventing access of water and grit from above upon the deck 9. The web 2 also preferably slopes outwardly from the boss 7, and the roof as a whole is free from grit- 10 retaining projections upon its upper surface. The depending end of the shaft 16 within the cap may also be bolted to the central boss 4, as shown. The runner may be provided with trunnions 18 fastened in blocks 15 19 formed at opposite sides of the frame 1, if desired. The shaft 16 may be suspended in any way suitable to permit of the rotation of the runner.

It will be apparent that by reason of the 20 closed unobstructed roof not only will the deck 9 be shielded from water and grit, but that whatever grit may get upon the upper surface of the roof will be readily thrown therefrom by the centrifugal force of the 25 runner and will not accumulate thereon and tend to cause local sagging of the runner. The result is that the runner-blocks wear away with substantial uniformity, and they may be used until they are all worn 30 down substantially to the surface of the bars.

The runner-blocks heretofore used have been of a rectangular circular or diamond shape. I have discovered that by making them hexagonal in cross-section, valuable 35 results will be secured. And I also prefer to so arrange the runner-bars that the individual blocks will stand in staggered relation to each other, as shown in Fig. 5.

I have found that by using runner-blocks 40 of a hexagonal form a more uniform distribution of the grit over the surface of the glass is obtained, while materially smaller quantities of grit are thrown out from under the edges of the runner. I believe this to 45 be due to the fact that as the grit tends to pile up against or be forced away from any face of a block, as such face is shifted relatively to the line of movement of the table beneath, the grit is distributed on the one 50 hand and confined on the other by the faces of adjacent blocks. Whereas when square or diamond shaped blocks are used, the tendency is for the grit to pass by the corners of the blocks, and thus to fly out at the

edges of the runner in materially greater 55 quantities. I believe the greater number of cutting edges in a hexagonal block to also be an advantage. But whatever the explanation may be, I have found that by the use of the runner herein described, plates of 60 glass may be ground materially faster than heretofore, at a materially less cost for materials and maintenance, and with a materially smaller percentage of breakage.

In order to attain the best results it is preferred to form the blocks on each bar with their adjacent edges standing obliquely to each other, as shown.

It is obvious that the construction herein described may be widely varied by those 70 skilled in the art without departure from the essential features of the invention as defined in the appended claims.

I claim as my invention:

1. In a grinding runner, the combination 75 with a rigid frame provided with a central boss, and a deck rigidly secured to said frame, of a closed impermeable roof extending over the frame and deck from the periphery of the frame to said central boss. 80

2. In a grinding runner, the combination with a deck having grinding blocks secured to its lower face, of a conical roof secured to and covering the upper surface of the deck and provided with a central opening. 85

3. In a grinding-runner, the combination with a metallic frame having radial arms, an inclosing wall, and a web having a central opening, of a cap closing said opening, a wooden deck secured to the arms and the wall, and grinding-blocks secured to the deck. 90

4. In a grinding-runner, the combination of a support provided with elongated grinding-blocks hexagonal in cross-section and symmetrical about their longitudinal and transverse axes, the blocks being arranged in parallel rows with their longitudinal axes in line with each other, and the blocks in adjacent rows of said parallel rows being in 100 staggered relation to each other.

In testimony whereof I have hereunto set my hand.

WARREN R. VALENTINE.
